Primary Examiner — Jennifer L Rempfer*(74) Attorney, Agent, or Firm* — Maschoff Brennan(57) **CLAIM**

The ornamental design for a neck pillow, as shown and described.

DESCRIPTION

FIG. 1 is a front view of a neck pillow according to the present application, showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof; and,

FIG. 9 is an enlarged view of a portion A in FIG. 7.

The broken lines represent the bounds of the detail view and form no part of the claim.
